United States Patent Office

Des. 223,076

Patented Mar. 7, 1972

223,076

ELECTRIC SHAVER

Robert O. Ernest, Oak Park, Ill., assignor to Sunbeam Corporation, Chicago, Ill.

Filed Jan. 11, 1971, Ser. No. 105,792

Term of patent 14 years

Int. Cl. D28—03

U.S. Cl. D95—3

Fig. 1.

Fig. 2.

Fig. 4.

Fig. 5.

FIG. 1 is a front, top and right side perspective view of an electric shaver, showing my new design;

FIG. 2 is a rear elevational view;

FIG. 3 is a side elevational view, the opposite side being substantially a mirror image thereof;

FIG. 4 is a top plan view as seen from a plane through line 4—4 in FIG. 3; and

FIG. 5 is a bottom plan view thereof as seen from a plane through line 5—5 in FIG. 3.

Portions of the drawing figures are stippled to indicate contrast in appearance.

I claim:

The ornamental design for an electric shaver, as shown and described.
